COMBINED TIME AND TEMPERATURE CONTROL

Filed April 21, 1927

UNITED STATES PATENT OFFICE

RAYMOND D. SMITH, OF PLEASANTVILLE, NEW YORK

COMBINED TIME AND TEMPERATURE CONTROL

Application filed April 21, 1927. Serial No. 185,563.

This invention relates to the automatic control of the flow of gas or other medium susceptible of variation in its rate of flow by altering the capacity of its conduit to permit such flow and by degrees, such for example as is effected by the opening and closing of a valve in a pipe line or by the increase and decrease of resistance in an electrical line; and particularly concerns the operation of a valve or other flow control jointly by timing mechanism and by heat sensitive mechanism or by either alone when desired.

An illustrative embodiment of the invention is hereinafter described and claimed with particular, though not exclusive reference to an application of the invention wherein the main heating burner of a gas oven, water heater, or the like, may be controlled selectively or jointly by time mechanism and by an associated thermostatic mechanism sensitive to the temperature in the oven or in the water being heated.

Reference is had to the accompanying drawings in which:

25 Fig. 1 shows in side elevation and partially in section a possible form of valve and its actuating mechanism including time and thermostatic controls together with an oven and its main burner part of the mechanism being broken away to make room for:

Fig. 2, which is a partial plan view looking downwardly on certain parts of Fig. 1.

Fig. 3 shows a modification of the construction of the valve mechanism.

35 Fig. 4 shows a specific modification of a part of the valve mechanism of Fig. 1.

Throughout the drawings different views of the same part are designated by the same reference numeral.

40 As the time controlled mechanism employed in this improvement may be of any kind desired I have chosen herein to illustrate a timing mechanism identical with that in my co-pending application Serial No. 157,733, and for the purposes of description herein need only explain that upon appropriate setting of time pointers 101 and 105 feeler levers 70 and 71 respectively are locked in position to intercept the rotative movement 50 of arms 47 and later unlocked manually or

by running of the time movement 99 as desired thereby to free arms 47.

When the arms 47 are intercepted they occupy one or another of four equally spaced points in their circular travel being advanced 55 from one to another of these consecutive positions in ninety degree increments of travel by the handle 62 as effected against the resistance of the detent roller 42 which normally seats itself in the crotch between successive teeth of the four pointed star wheel 41 whereby arms 47 receive their normal definite positioning as aforesaid.

Gear 53 turns fixedly with arms 47 and is in mesh with pinion 54 fast on the crank 30 65 so that each quarter revolution of arms 47 produce a half revolution of crank 30 whereby valve 10 is alternately opened and closed upon respective quarter turns of handle 62 except when feelers 70 or 71 are locked by the 70 timing mechanism in which event arm 47 is held from rotating with handle 62 which latter consequently advances and is held in a position energizing band spring 51 to cause later, time controlled escapement of arm 47 75 automatically to actuate the valve.

As the above described details are not material to the present invention it will suffice to consider valve 10 openable and closeable by handle 62 with or without the medium of 80 time control and through the following mechanism which is more particularly concerned with the present improvement.

Valve 10 consists of a body portion containing the dividing partition 13 in which 85 is the orifice 14 to and away from which the piston 19 may be moved by vertical sliding of the stem 17 loosely guided in the bonnet 16 and steadied at its lower extreme end 18 by a guide boss 110 formed in the valve casting. 90

Stem 17 is slideable up and down in response to actuation by the timing mechanism hereinbefore described and is turnable on its axis by the heat control mechanism next to be described; either of which movements of stem 95 17 causes upward or downward movement of piston 19 relative to orifice 14.

The vertical up and down movement of stem 17 is accomplished by the connecting bail 29 hinged on the eccentric portion of 100

crank 30 and pivotally engaging a collar 58 freely slideable on stem 17 and serving to transmit the upward pull of bail 29 through the medium of compression spring 56 acting between collar 58 and the enlarged head 57 of stem 17 and serving to transmit the downward thrust of bail 29 through the medium of compression spring 59 acting between collar 58 and the lower thrust washer 60 beneath which is pinned rigidly to stem 17 the long, small diameter gear 112 which remains in mesh with a segment 113 whatever the vertical position of stem 17, the teeth of gear 112 freely sliding through the teeth of segment 113 in the up and down movements of stem 17. The portion of stem 17 near its bottom end whereat is carried the piston 19 is formed as a screw 114 to fit a correspondingly threaded hole in piston 19 which latter is kept from rotating by the fact of a notch 115 being engaged by a fin 116 projecting from the interior wall of valve 10 so that upon rotation of stem 17, piston 19 being thus held from rotating will instead, work either upwardly or downwardly on the screw portion 114 of stem 17. Stem 17 further carries at a fixed point thereon the auxiliary seal piston 117 whose function it is in the uppermost position of stem 17 to press against the bonnet seat 24 to seal the stem opening through the bonnet against possible escape of gas when piston 19 is absent from its seat 22.

There remains to be described the mechanism by which segment 113 is swung to effect the opening or closing movement of piston 19 to a degree corresponding to some temperature it may be desired to maintain in say, an oven, the wall of which I have indicated at 118. Such oven may be heated by burner 119 having ports 120 and supplied with gas through the orifice 121 as regulated by piston 19 in its movements to and from the seat 22 of valve 10. Entrance for the air 45 to mix with the gas so delivered through orifice 121 is provided by openings 122 which may be adjustable to regulate the mixture in the usual way.

A pilot burner 123 may be positioned to 50 ignite the burner 119 and derive its supply of gas through a tube 124 connected into the supply side of valve 10 so that pilot 123 may remain permanently burning irrespective of whether valve 10 is open or closed.

I may mount a bracket 125 on the housing 55 of the timing mechanism which is supported by the valve body 35 or on the oven wall 118 which with a lower bracket 126 will afford bearing for the upright shaft 127 pinned to segment 113 for rotating the same and carrying at its upper end a cam 128 and hub 129 of which is likewise pinned to shaft 127. The upper bracket 125 carries a mounting 130 in which is mounted by threaded engagement 65 the thermostatic tube 131 of expandible ma-

terial such as copper or brass at the opposite end of which is rigidly secured one end of a relatively non-expansive element or rod 132 of porcelain or other suitable material which may slide in a bearing in bracket 125 70 and have its opposite end thus guided in accurate position to act upon cam 128, the latter having a rotative tendency imparted to it by spring 133 keeping it closeted against the end of rod 132. Rotation of tube 131 by 75 means of the graduated wheel 134 will shift the position of tube 131 longitudinally because of its threaded mounting and thereby vary the action of rod 132 in its positioning of cam 128, hence segment 113, hence the vertical position of piston 19 on valve stem 17 and this effect may be indicated by a stationary pointer 135 as is common practice in the art of heat regulated valves.

The operation is as follows:

Fig. 1 shows valve 10 closed because of the position of handle 62 and the crank 30. Therefore no gas is delivered to burner 119, oven 118 is cold, thermostatic tube 131 has shortened overcoming spring 133 swinging segment 113 clockwise in Fig. 2 rotating gear 112 contra clockwise in Fig. 2 thereby pulling piston 19 as far upwardly on the threaded portion of stem 17 as it is designed to go, spring 59 compensating to avoid 95 any positive jam of piston 19 downwardly against its seat 22. Let us now open the valve by a quarter turn of handle 62 either directly responsive to such handle movement or consequent thereupon after an intervening period of time if we choose to make use of the timing mechanism hereinbefore described. The resulting quarter turn of gear 53 results in a half turn of pinion 54 which shifts crank 30 to its uppermost or dotted line 100 position thus raising valve stem 17 and piston 19 to open orifice 14 all of which movement is transmitted through the compression spring 56 on the valve stem by the tension in which, auxiliary or seal piston 117 is brought against 105 the bonnet seat 24. In this position of parts a full supply of gas is delivered through orifice 121 to burner 119 which ignites from pilot 123 and proceeds to heat oven 118. As the 110 temperature rises tube 131 expands drawing rod 132 to the right permitting contra clockwise rotation of segment 113 under action of spring 133 in Fig. 2 which turns gear 112 and hence stem 17 clockwise in Fig. 2 which by the 115 action of screw threads 114 in piston 19 gradually forces the latter downwardly to check the flow of gas through orifice 14 against the action of spring 133 until finally the consequent reduction of gas supplied to burner 119 reduces the oven temperature to a point 120 where the consequent cooling of thermostatic tube 131 swings the rotating parts in the opposite direction and turns screw 114 likewise in the opposite direction to increase the supply of gas through orifice 14 by again raising 125

piston 19; this compensating action re-occurring in respectively alternate directions to the effect of maintaining the temperature in oven 118 at approximately the designed point indicated by pointer 135 on the graduated wheel 134.

It will be understood that in any condition of the heat control of piston 19, the latter may always and at any time be closed downwardly against its seat by dropping of stem 17 either by direct manipulation of handle 62 or through the intervention of time control in association therewith and that in no case will this result in strain or jamming of the several mechanical parts for if stem 17 be given a tendency to drop at a time when the rotative position of stem 17 as caused by heat control had run piston 19 rather far downwardly on threads 114 thus preventing the full drop of stem 17, handle 62 can nevertheless be rotated to and held in its valve closed position the actual dropping of stem 17 and corresponding rotation of crank 30 being deferred until the cooling of the oven swings the heat controlled part so that stem 17 turns in its threaded engagement with piston 19 as the cooling of the thermostat causes this turning followed up by a gradual dropping of stem 17 under the impulse of band spring 51 until the normally closed position of valve 10 with the thermostat cool obtains as pictured in Fig. 1.

It should be explained that the ability of the crank 30 to raise and lower stem 17 without binding or cramping, regardless of the vertical position of piston 19 on its threads 114, is well accomplished by the yielding of compression spring 59, alone, and without dependence on the backward yielding of band spring 51 so that if the latter failed to function, or in fact were entirely omitted in the design and in its stead a rigid operating connection established between handle 62 and gear 53 or crank 30, the handle 62 could still be manually positioned at its definite stations determined by star wheel 41 and roller detent 42, alternately sealing and unsealing orifice 24 by means of seal piston 117 which in Fig. 1 is shown pinned to stem 17 and in Fig. 4 not so pinned but permitting valve stem 17 to rotate for the heat control function without corresponding rotation of seal piston 117 when the latter is pressed upwardly against seat 24. Escape of gas is effectually sealed by pressure against stem 17 of the relatively soft washer made of leather or other suitable material carried in the recess in the upper face of piston 117 which contacts with seat 24, whether or not stem 17 has any other fluid-tight packing in its bearing in valve bonnet 16.

The adjustment for operation is preferably such as to make it impossible for piston 19 to be screwed upwardly far enough to lift same away from its seat 22 by any action of

thermostat 131—132 unless the seal piston 117 is upwardly positioned against its seat 24; this precluding escaped gas between stem 17 and its bearing hole in bonnet 16 should no packing at that point be employed.

To make the opening and closing of orifice 14 a more gradual function of piston 19 in its movement I may form the latter as a cone as shown at 19' in Fig. 4 and the seat 22' to correspond if desired.

In the foregoing I have shown how a single valve may be subjected to a combination of control by timing mechanism and by heat sensitive mechanism through the joint and separate actions of such two mechanisms on a single movable element of the valve. In Fig. 3 I show how a single valve may be subjected to this combination of control in an arrangement where the timing mechanism operates one movable element of the valve and the heat governed mechanism operates a separate, associated movable member of the same valve.

In Fig. 3 the burner is indicated at 140 having ports 141 and entrance for the air through openings 142 in the mixture adjusting cap 143. Gas is led to burner 140 through a main conduit which I have indicated in cross section at 144 transverse the opening 145 in which, is the adjustable needle valve housing 146 turnable in threaded engagement with the thickened walls of conduit 144 for sufficient length to produce a seal against the escape of gas. Valve housing 146 carries at its top end the gear 147 in mesh with segment 113 as is the gear 112 on stem 17 and which when rotated by said segment raises or lowers valve housing 146 in its threaded mounting and with it the valve seat 148 carried at its bottom end into the opening 149 of which the point of a needle valve 150 may project, this needle valve comprising the bottom terminus of the valve stem 17' operated upwardly and downwardly by the bail 29 just as in the case of stem 17 in Fig. 1. The operation of this modification pictured in Fig. 3 is as follows. Gas delivered through the conduit opening 145 is admitted through ports 151 in the wall of valve housing 146 and is conducted through flutes 152 cut in the lower part of stem 17' to the interior cavity 153 of the housing 146 and there retained or hence permitted to flow out into burner 140 through orifice 149 depending on whether needle 150 is closeted against its seat. Obviously the alternate lifting and lowering of stem 17' through the connection of bail 29 as actuated by crank 30, respectively opens and closes orifice 149 to deliver or shut off gas from burner 140. If stem 17' be lifted and needle valve 150 raised from its seat 148 the supply of gas permits burner 140 to heat oven 118 or any other desired compartment, or medium, or material to which thermostatic tube 131 is sensitive whereupon the

consequent movement or swing of segment 113 rotates valve housing 146 so that the needle seat 148 screws upwardly to reduce the amount of opening between needle valve 150 and said seat which will cut down the supply of gas, reduce the temperature acting upon tube 131 which in turn will operate segment 113 to screw housing 146 downwardly again and increase the supply of gas to burner 140 whereby an approximately constant temperature will be maintained in whatever is heated by burner 140, the temperature being determined by the setting of graduated wheel 134 as in the case of the arrangement shown in Fig. 1.

It will be obvious to those skilled in the art that the timing mechanism and the thermostatic mechanism may be of any of numerous styles and that their positional relation to each other, to the controlled valve, and to the oven 118 or other device to be heated may be varied at will. It will also be understood that the present invention is in no way limited to any of the details of construction herein disclosed to illustrate a possible embodiment and that the following claims are not intended to limit the claimed combinations to any of the particular devices and arrangements pictured and described.

30 Among the departures and modifications possible the following mention will be clear. I may arrange a timing mechanism to automatically under time control vary the setting of graduated wheel 134 or other means for 35 varying the temperature at which oven 118 will be automatically maintained by the heat sensitive device 131, 132. This would be useful for instance, in the cooking of foods where, after a designed initial period of 40 cooking at relatively high temperature the time mechanism would automatically operate to shift the setting of wheel 134 and cause the oven thereafter to be maintained at a lower constant temperature for finishing the 45 cooking, after which the gas may be entirely shut off by second automatic action of the timing mechanism.

I may substitute an electric switch to control the current to an electric heating unit 50 that will take the place of burner 119 and arrange electric contacts of such a switch to be alternately closed and opened by the vertical movements of stem 17 subject to time control as herein and I may provide a rheostat 55 to be caused to introduce varying degrees of resistance or to produce other electrical effects designed to vary the heat given off by the said unit consequent upon the rotative movement of stem 18 under the action of 60 thermostatic device 131, 132.

I may further insure against the escape of 65 gas elsewhere than into burner 140 in Fig. 3 by housing the entire mechanism or any convenient parts thereof exterior of burner 140

in a gas tight enclosure as is common in the art.

I may within the scope of this invention employ a timing mechanism of the type disclosed in my co-pending application Serial No. 150,278 wherein the actuation of the valve is effected by the time setting pointers and I may combine with the time and heat controls of the present improvement safety shut off devices of any of the types disclosed in my above said application or in my previously mentioned co-pending application Serial No. 157,733, or others to prevent the gas from being on in the event pilot burner 123 becomes accidentally extinguished.

In reference to the following claims it is pointed out that the timing mechanism which I have chosen to disclose operates at one manual setting automatically to turn on the gas and to shut off the gas at any two separate and selected times in the period between which the thermostat will maintain the oven heat at a set temperature. The invention therefore contemplates the starting of cooking at a predetermined time as determined by time mechanism, the control of that cooking as to temperature by automatic thermostatic means and the stopping of the cooking again by timing mechanism. It is equally within the scope of the present improvement however, to provide that the timing mechanism shall alone turn on or shut off the gas and that if a timing mechanism is employed capable only of turning on the gas the heat control may be arranged merely to turn off the gas and keep it turned off upon the attainment of a certain critical temperature the subsequent lowering of which will not operate the thermo-dynamic means to re-open the valves.

I claim:

1. In a valve, in combination, a seal piston, a stem longitudinally slidable in a bearing to operate said seal piston, a seat to be contacted by said piston for preventing the escape of gas through said bearing, a flow governing piston operated by said stem in relation to said seal piston and to said seat, and heat sensitive means arranged to operate said flow piston without displacing said seal piston from its seat.

2. In a valve, in combination, a seal piston, a stem longitudinally slidable in a bearing to operate said seal piston, a seat to be contacted by said piston for preventing the escape of gas through said bearing, a flow governing piston operated by turning movement of said stem, hand actuated mechanism arranged to slide said stem, and heat operated mechanism arranged to rotate said stem.

3. In a valve, in combination, a seal piston, a stem longitudinally slidable in a bearing to operate said seal piston, a seat to be contacted by said piston for preventing the escape of gas through said bearing, a flow governing

- piston operated by said stem in relation to said seal piston and to said seat, timing mechanism to operate said stem longitudinally and thermo-dynamic mechanism to effect rotative movement of said stem.
5. In combination, a contained medium to be heated, a heating unit for said medium, thermostatic means sensitive to the temperature of said medium, a regulator to predetermine and vary the effect of temperature upon said means, a governor for said unit and actuatable by said thermostatic means, timing mechanism, and means rendering said governor, but not said regulator, conditionable by said timing mechanism.
10. In combination, a gas oven, a burner for heating said oven, a valve having a stationary body connected in a pipe line and having movable parts controlling the flow of gas to said burner, timing mechanism remote from heat in said oven, thermostatic mechanism including a member sensitive to heat in said oven, connections whereby said timing mechanism operates said valve independently of said thermostatic mechanism, and connections whereby said thermostatic mechanism operates said valve.
15. A combined time and temperature control for gas ranges comprising in combination with a heating burner, a thermostat disposed to be sensitive to heat generated by said burner, a timing mechanism, and a valve governing the supply of gas to said burner and connected by mechanical parts both to said thermostat and to said timing mechanism and actuatable in common thereby.
20. In combination, a valve including a part movable to increase and to decrease a flow through a variable port in a conduit, timing mechanism, a non-yielding mechanical part constituting at one point the sole means of operative connection between said mechanism and said valve, and thermo-dynamic means, also connected operatively with said valve part and solely by means of said non-yielding mechanical part at said point in said connections.
25. In combination, a valve including a part movable to vary the flow through a port in a conduit, timing mechanism, a thermostatic device, a non-yielding connecting member for operating said valve part, a power transmitting medium between said member and said timing mechanism, and an operatively separable power transmitting medium between said valve part and said thermostatic device.
30. A combined time and heat controlled valve having in combination, a single valve member movable to open and close a port in a conduit, time mechanism, a set of transmission parts including a means for mechanical slippage and connecting said mechanism with said valve member, a heat governed device, and another set of transmission parts connecting said device with the
- said valve member, said means for mechanical slippage permitting said device alone to move said valve member by means of its said set of transmission parts.
35. A combined time and heat controlled valve having in combination, a single valve member movable to open and close a port in a conduit, time mechanism, a set of transmission parts connecting said mechanism with said valve member, a heat governed device, another set of transmission parts and including a means for mechanical slippage and connecting said device with the said valve member, said means for mechanical slippage permitting said time mechanism alone to move said valve member by means of its said set of transmission parts.
40. In combination with thermal mechanism and timing mechanism for actuating in common a single conduit control, a member of said control connected by a yielding mechanism to be movable with said time actuating mechanism when acted upon by the latter, and further connected by non-yielding mechanism to be moved relative to said time mechanism when acted upon by said thermal mechanism.
45. In combination with thermal mechanism and timing mechanism for actuating in common a single conduit control, a member of said control connected by a yielding mechanism to be movable with said thermal mechanism when acted upon by the latter, and further connected by non-yielding mechanism to be moved relative to said thermal mechanism when acted upon by said timing mechanism.
50. In a combined time and temperature control mechanism, a valve actuatable in common by time and temperature effects working through said mechanism, means to set a portion of said combined mechanism so that the action of temperature change upon said valve shall be one of degree and means to set another portion of said combined mechanism so that the action of time upon said valve shall be either to render operative or inoperative upon said valve the said action of temperature.
55. In combination, a conduit control having full open and full closed positions, a timing mechanism tending to effect one or the other of said positions and a thermal mechanism connected to actuate said control to cause degrees of opening thereof intermediate its said two positions.
60. In combination, a gas oven, a burner for heating said oven, a valve having a stationary body connected in a pipe line and having movable parts controlling the flow of gas to said burner, timing mechanism remote from heat in said oven, thermostatic mechanism including a member sensitive to heat in said oven, connections whereby said timing mechanism operates said valve independently

of said thermostatic mechanism, connections whereby said thermostatic mechanism operates said valve, and a hand setting device arranged to act between said member of the thermostatic mechanism and the last said connection thereby to vary the effect of said thermostatic mechanism upon said valve responsive to a given temperature in said oven.

16. A combined time and heat controlled valve having in combination, a single valve member movable to open and to close a port in a conduit, time mechanism, a heat governed device, two sets of transmission parts one of which connects said mechanism with said valve member and the other of which connects said device with said valve member, each of said sets of transmission parts having a means permitting mechanical slippage, thereby to allow the other set of transmission parts to act independently for operation of said mechanism alone or of said device alone upon said valve member.

Signed at Pleasantville, New York, this 20th day of April, 1927.
